UNITED STATES PATENT OFFICE

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY

SEWING MACHINE

Application filed July 8, 1927, Serial No. 204,278, and in Great Britain July 20, 1926.

This invention relates to sewing machines for use in the manufacture of boots or shoes and is particularly concerned with curved needle machines for stitching together the 5 sole and upper of turn shoes. It has especially in view the improvement of that class of machine which is used to sew turn slippers without previous lasting and is described in Patent No. 1,163,558, dated December 7, 1915 10 and in Patents Nos. 1,188,388 and 1,188,389, dated June 27, 1916.

The present invention has for its objects to provide a machine of this class of simple and light construction as a whole and to provide 15 improved forms of and actuating mechanisms for sewing and work feeding devices of machines of this class to adapt the same for running at comparatively high speed and render the same well capable of operating 20 upon material of inferior quality without damaging the material (for instance by pulling the stitches through the material as is liable to occur with the heavy machines today in use) while also capable of sewing material of good quality in as satisfactory a 25 manner as with machines heretofore in use.

Such slipper turn shoes as referred to above may require to have sewn to the upper by the sewn seam either a felt or rubber sole 30 or a combination sole of felt or rubber and leather or a sole composed only of leather.

Other objects and the various novel features of the invention will become apparent to those skilled in the art from the following 35 description given by way of example of one form of machine according to the invention and embodying its various features in particular forms thereof. The said form of machines has sewing instrumentalities of the 40 nature and functioning in the same general way to sew a chain stitch seam in work in a horn as the machines in customary use for slipper turn shoe sewing and the original form of which machine is described in the 45 earliest dated of the aforementioned patents.

In the accompanying drawings, Fig. 1 is a view in side elevation of the machine; Fig. 2 is a view in front elevation; Fig. 3 is a detail view illustrating the relative arrangement 50 of the work supporting horn, the needle,

the presser, the back rest and the feed point; Fig. 4 is a detail view in side elevation illustrating a modified form of feed point or foot with which the machine may be provided when shoes having channeled insoles are to be operated upon; Fig. 5 is a detail view in front elevation of certain of the parts illustrated in Fig. 4; Fig. 6 is a plan view of the parts illustrated in Fig. 5; and Fig. 7 is a detail view in side elevation of the mechanism 55 for actuating the feed point.

The novel machine comprises a base 1, adapted to be fixed to a work bench or pedestal, which base has clamped in it so as to be adjustable vertically a vertical stem formed 60 on a frame to the upper face of which is bolted a machine head 2.

The head has on it spaced uprights respectively carrying two bearings in which is rotatably mounted a horizontal driving or cam 65 shaft 3 extending across the machine. The driving shaft has rotatably mounted on it at its right hand end a driving pulley 4 which is adapted to be clutched to the shaft by a clutch of the type illustrated and described in the patent to Jerram 1,124,620, dated January 12, 1915. On the opposite end of the shaft is a hand wheel 5 by which the driving shaft may be rotated. The clutch is enclosed in a substantially cylindrical casting 70 extending from the right-hand upright of the head and a rod 6 passes from the clutch to a treadle for controlling the clutch. Between the clutch and hand-wheel the head encloses a number of cams and eccentrics which 75 operate the sewing and feeding devices of the machine.

The frame carries a rotatable horn 7 on which the work is supported during the 80 sewing and the horn is substantially of the shape and disposition of, and is controlled in a similar manner to that shown in Patent 1,188,388 above referred to. A curved hook needle 8 is fixed in an arm 9 which projects 85 from a horizontal stud or spindle extending across the frame and rotatably mounted at the front of the head. The arm has pivotally connected to it one end of a rearwardly extending curved link 10 the other end of which is pivotally connected to the front end 90 of

of a needle-actuating arm 11 which extends back under the cam shaft to a point behind and below the latter where it is pivoted on a shaft 12, extending across the machine, 5 rotatably mounted at the rear of the head. The needle-actuating arm has pivotally connected to it between its pivot and its connection to the link the lower end of a cam link 13 the upper end of which has formed on 10 it a rectangular strap 14 surrounding a four-way cam on the cam shaft. Pivotally mounted on the head concentrically with the needle is a needle guard 15 of usual construction and actuated by the needle arm as 15 usual.

A tubular looper 16 having an offset thread-delivery end is mounted to rotate about its axis in an arm 17, secured within the frame and pivoted on a horizontal stud 20 18 (transverse to the looper axis) extending across the machine and fixed in the head. The looper arm 17 is mounted on an eccentric portion of the stud and the stud has fixed on it, outside the frame, an arm 180 carrying 25 a spring plunger 19 which is adapted to enter one or other of a series of holes in the frame to hold the stud in adjusted position. By this means the looper arm 17 may be 30 adjusted to bring the looper into proper relationship to the needle. The looper axis extends in its vertical plane upwardly and forwardly from its delivery end at an angle of some sixty degrees to the horizontal and its axis is in the plane of the curved hooked 35 needle. To rotate the looper about the needle, the looper has formed on its gear teeth which mesh with a rack bar 190 slidably mounted in the arm 17 and connected by a link 20 to the strap 14 of the needle actuating 40 mechanism.

A thread finger 230 operating in the usual way is fixed, inside of the head, on the end of a horizontal shaft extending across the machine and rotatably mounted in a bearing 45 on the head.

When operating upon shoes having a combination leather and felt sole the shoe is fed over the horn tip through the machine by a feed point which digs into the upper and 50 the felt of the sole inside the line of the seam. The feed point indicated at 23 is fixed in the lower end of a vertical bar 24 slidably mounted in a vertical bearing which is formed on the forward end of a horizontal, 55 rearwardly extending feed lever 25 pivoted about mid-way of its length on a vertical pivot 26 fixed in the head under the cam shaft. The axis of the vertical pivot 26 is in a vertical plane passing through the 60 axis of the cam shaft. The vertical bar 24 has rotatably mounted in it a horizontal pin 27 extending across the machine and through vertical slots at each side of the bearing. The pin is bored perpendicularly at each side 65 of the bearing and has sliding through it,

one at each side of the bearing, two horizontal pins 28 which extend forwardly from a cam lever 29. The cam lever 29 extends rearwardly of the machine and is pivoted below the cam shaft on a horizontal pin extending across the machine and carried by the feed lever 25. The cam lever 29 at its rear end carries vertically beneath the cam shaft axis a cam roll which enters a cam groove formed in a cam on the cam shaft. By this means the feed point is given rising and falling movements. To obtain the lateral movements of the feed point to feed the work the feed lever 25 is extended rearwardly from its vertical pivot in the head and at its rear end behind the cam shaft carries a vertical pin 30 which extends upwardly through a bearing in and between the ends of a cam lever 31 to pivotally connect the two levers. The cam lever 31 extends horizontally forwardly and rearwardly from the pin above the feed lever and at its forward end carries a vertical cam roll which immediately beneath the cam shaft enters a cam groove in a cam on the cam shaft. The rearward extension of the cam lever 31 has in it a slot which receives a vertical pin 32 extending downwardly from a horizontal rack bar 33 slidably mounted in a guideway extending rearwardly and forwardly of the machine in the head. The rack bar 33 is adjusted forwardly or rearwardly by a pinion on the shaft 12 at the rear of the machine, which pinion is rotated by a hand-wheel 34 fixed on it. By adjusting the rack bar 33 in its guideway the pin 32 on the rack bar which acts as a fulcrum for the cam lever 31 is moved in the slot nearer to or farther from the cam roll and the throw of the pin 30 which connects the cam lever 31 to the feed lever 25 is thereby varied and the lateral movement of the feed point also varied. When the feed point is at the end of its feeding movement, that is at the end of its movement towards the left viewing the machine from the front and closest the needle the slot in the cam lever 31 and the guideway in the head are in alignment so that in any position of the pin in the slot the feed point is always moved to the same place at the end of the feed stroke and the difference in length of feed takes place at the opposite end of the stroke.

A presser or bender 35 is pivoted on an eccentric portion of a horizontal stud 36 fixed in the head to extend from right to left so that by rotating the stud the heightwise and forward or rearward position of the presser may be adjusted. The presser is forked so as to engage the work at each side of the needle and bends down the edge of the shoe so as to position and hold it on the horn tip while the needle enters the work and the presser holds the work while the needle is retracted.

The presser has a depending arm to which

is pivotally connected the forward end of a rearwardly extending rod 37 passing under the cam shaft the rear end of which slides through a pin 38 rotatably mounted in a 5 downwardly extending arm of the lever 11. The rod has on its rear end a nut between which and the rear side of the pin 38 is a spring 39 surrounding the rod which yields after the presser engages the work.

10 A thread take-up lever 40 is pivoted on the head on a horizontal stud extending across the machine one arm of the lever carrying a roll over which the thread passes and the other arm carrying a cam roll which enters 15 a cam groove in a cam on the driving shaft.

An auxiliary take-up 41 operates between the main take-up and the thread supply and comprises a depending arm pivoted on a horizontal stud extending across the machine 20 and fixed in the head. Extending upwardly from the hub of the arm is a short arm which engages a spring plunger 42 mounted in the head. Movement of the arm under the influence of the spring plunger is limited by 25 an adjustable screw 43 in the head. A second spring pressed plunger 44 in the head engaging the short arm increases the resistance of the auxiliary take-up near the end of its movement under the pull of the thread.

30 When operating upon work having a felt upper and channelled leather insole the feed point is displaced by a feed foot or channel guide 45 which is fixed to the left-hand end (as seen by the operator) of one arm of a 35 horizontal lever 46 pivoted upon a vertical pin 47 and extending from right to left of the machine. The vertical pin 47 is carried at the front end of one arm of a cam lever 48 which is pivoted on a horizontal stud extending 40 from right to left of the machine and fixed at the lower end of the vertical bar hereinbefore referred to as carrying the feed point which bar in this case is fixed in its bearing on the feed lever 25. The rear end 45 of the other arm of the cam lever 48 carries a cam roll which immediately beneath the cam shaft, enters a cam groove in a cam on the cam shaft to raise and lower the foot out of and into the channel. The to and fro feed movements of the foot are effected by 50 lateral movement of the vertical bar to which the cam lever is pivoted as in the case of the feed point above described. The right hand end of the other arm of the lever 46 to which 55 the feed foot is fixed is held by a spring 49 against a cam surface 50 fixed on the head so that as the feed foot is moved to feed the work the arm rides over the cam surface and the feed foot instead of being moved in a 60 curved path about the axis of the feed lever is caused to move in a straight line. The feed foot remains in the channel to support the work against the thrust of the needle as it penetrates the work.

65 When operating upon combination felt and

leather soles, a back gauge 51 is provided. A portion of the work engaging face of the back gauge is curved forward so as to bend down the work as it moves past it into the path of the presser.

70

When operating upon a shoe having a felt sole the work may be fed by the needle which will be given lateral movement in addition to its work penetrating movement. For this purpose the needle spindle may be 75 slidingly and rotatably mounted in the head and connected to the feed lever hereinbefore referred to so as to be moved laterally to feed the work. The horn and presser in this latter case may be of the shape and 80 operated in a similar manner to those shown in Patent No. 1,163,558 above referred to.

The construction and arrangement described is one that results in the machine having most of its mechanism in a comparatively restricted space generally speaking beneath the level of the cam shaft and behind a vertical plane parallel to the cam shaft and through the working position. Thus save for the auxiliary take up and the front 85 arm of the main take up lever, none of the thread and work handling parts of the machine or the link, lever or like mechanism connecting the same with the cams or the like on the cam shaft lie above a plane containing 90 the cam shaft axis and extending upwardly and rearwardly at some 20° only to the horizontal. Again, none of such parts except the looper itself and the roll of the main take-up extend substantially forward of a vertical 95 plane parallel to the cam shaft and passing through the horn tip.

The following particulars of the relative timing of the parts will further indicate the 100 nature of the movements:

The machine has a definite stopping point 105 which will be considered as the zero position. The needle is then fully retracted and stays so until the cam shaft has turned 65° when it advances to reach forward position 110 105° later staying forward then during 55° of cam shaft rotation when it commences to move back and reaches its fully retracted position 25° before the cam shaft rotation is completed in which position it then stays. 115 The looper occupies 45° of cam shaft rotation and 290° of its own rotation in laying the thread fully round the needle from the time it first brings the thread in contact with the side of the needle which occurs after the needle has remained fully advanced for 20° of cam shaft rotation and after the looper has itself moved some 160° from its starting position. The thread finger is forward until the cam shaft has rotated 135° when it retires during 35° to stay back during 90° and then advances during 45° to stay forward for the remainder of the cycle. The feed movement occupies 55° of cam shaft rotation 120 of which the first five degrees actually occur 125 130

during the last five degrees of cam shaft rotation to the zero position above adopted. The feed member stays in its left hand extreme and in its depressed positions until the cam shaft has turned 185° from the zero position when the needle is fully advanced. Then during 5° of cam shaft rotation the feed member lifts and thereafter returns during 40° of cam shaft rotation to its starting position where it dwells, lifted, during 70° of cam shaft rotation to then fall during 10° and thereafter dwell in that position for 45° . The main take up occupies 180° in rising and 180° in falling reaching its fully lifted position (i. e. the end of its pulling movement) at about 180° from said zero. The presser is in raised position at the beginning of the cycle for 50° when during 20° it falls to engage the work before the needle enters it and then stays down during 165° of cam shaft rotation when after the cam shaft has rotated 235° from zero position it commences to lift to reach its fully raised position just at the end of the cycle.

25 Certain features of the machine not claimed herein form the subject-matter of a divisional application Serial No. 644,444 filed November 26, 1932.

Having thus described the invention, what is claimed is:

1. A sewing machine having, in combination, a horn arranged to extend within and support a shoe, stitch forming devices including a curved needle arranged to pass through the work in a path substantially parallel to the work engaging surface of the horn, and means for feeding the work including a feed point arranged to engage the work inside of the line of the seam, and means for moving the feed point into and out of engagement with the work and back and forth in the line of feed.

2. A sewing machine having, in combination, a horn arranged to extend within and support a shoe, stitch forming devices including a curved needle arranged to operate in a fixed plane and to pass through the work in a path substantially parallel to the work engaging surface of the horn, and means for feeding the work including a feed point, a feed point carrier, means for moving the feed point on the carrier into and out of engagement with the surface of the shoe sole, and means for actuating the carrier to move the feed point back and forth in the line of feed.

3. A sewing machine having, in combination, stitch forming devices, a feeding device movable into and out of engagement with the work, a feed lever on which the feeding device is mounted the pivotal movement of which produces movement of the feeding device in the line of feed, a cam actuated actuating lever for the feed lever, an adjustable fulcrum pin for said cam actuated lever, a carrier for the said fulcrum pin, and means

for adjusting said fulcrum pin to vary the feeding movement of the feed lever.

4. A sewing machine having, in combination, a horn arranged to extend within and support a shoe, stitch forming devices including a curved needle arranged to pass through the work in a path substantially parallel to the work engaging surface of the horn, a channel guide, a lever to which the channel guide is secured, a feed lever upon which the channel guide lever is pivotally mounted, means for actuating the feed lever to impart feeding and return movements to the channel guide, and a fixed cam engaging the channel guide lever to cause the channel guide to move in a straight line.

In testimony whereof I have signed my name to this specification.

ARTHUR BATES.
